UNITED STATES PATENT OFFICE.

HENRY V. WILLE, OF PHILADELPHIA, PENNSYLVANIA, ASSIGNOR TO THE BALDWIN LOCOMOTIVE WORKS, OF PHILADELPHIA, PENNSYLVANIA, A CORPORATION OF PENNSYLVANIA.

BOILER.

1,363,944.

Specification of Letters Patent. Patented Dec. 28, 1920.

Application filed May 9, 1917. Serial No. 167,445.

To all whom it may concern:

Be it known that I, HENRY V. WILLE, a citizen of the United States, residing in Philadelphia, Pennsylvania, have invented 5 certain Improvements in Boilers, of which the following is a specification.

My invention relates to certain improvements in the manufacture of boilers having flanged heads, particularly of the locomotive type in which the back head of the fire box, as well as the rear top sheet, is flanged and is secured to the crown sheet and to the 10 side walls of the fire box by welding. In this type of boiler there is also a welded 15 joint between the extension of the combustion chamber and the fire box.

The object of the invention is to design the boiler so that the back fire box head and the rear tube sheet will have a deeper flange 20 than heretofore so that the weld will be between the first and second rows of stay bolts, and also to design the other parts where the weld is located so that both sheets are supported by stay bolts.

25 In the accompanying drawings:

Figure 1 is a longitudinal sectional view of the rear portion of a locomotive boiler illustrating my invention;

Fig. 2 is a detached perspective view of 30 the back fire box head showing a row of stay bolt holes in the flange, the stay bolt holes in the body of the sheet being omitted to avoid confusion; and

Fig. 3 is a perspective view of the rear 35 tube sheet showing the flange perforated for a row of stay bolts.

Heretofore, it was the common practice to flange the back fire box head, as well as the rear tube sheet, and to attach the flanges to 40 the body portion of the fire box by rivets, then, when the welding was perfected, these flanges were butt-welded against the sides of the crown sheet and the fire box, but, in every instance, the weld was beyond 45 the line of stay bolts which connected the wall of the fire box structure with the outer wall of the boiler, therefore, great care had to be exercised in properly making the head, as the joint was supported wholly by the 50 stay bolts on one side of the weld.

By my invention, both the flange and the body portion of the fire box structure are supported by a row of stay bolts, thus reducing considerably the strain on the flanged

portion of the back head of the fire box and 55 the rear tube sheet.

Referring to the drawings, 1 is the main shell of the boiler at the fire box. 2 is the back boiler head. 3 is the barrel of the boiler having a flanged section 4 at the bottom. 5 is the mud ring extending around the base of the fire box structure of the boiler. 6 is a side wall of the fire box. 7 is the crown sheet. 8 is the front flange paralleling the portion 4 of the barrel. 9 65 is the rear tube sheet and 10 is the back fire box head.

In the present instance, the fire box 11 has a deep combustion chamber 12 at the forward end of which is the rear tube sheet. The back 70 has a deep flange 9^a shown clearly in Fig. 3. This rear tube sheet is welded to the body of the combustion chamber 12 on the line *x* between the first row of stay bolts 13 and the second row of stay bolts 14. The back fire 75 box head has a deep flange 10^a, as clearly shown in Fig. 2, and is welded to the body portion of the fire box on the line *y* between the first row of stay bolts 15 at the rear of the body portion and the second row of stay 80 bolts 16.

It will be noticed, upon referring to Fig. 3, that there is a line of stay bolt holes in the flange 9^a of the rear tube sheet 9 and that there is also a row of stay bolt holes in 85 the flange 10^a of the back fire box head 10. This fire box structure is first welded and is then mounted in the rear of the locomotive boiler and the stay bolts are located at certain intervals at each side, connecting the 90 shell of the fire box with the shell of the boiler, consequently, the first row of stay bolts at the rear tube, as well as the first row of stay bolts at the back head of the fire box, take the greater portion of the strains to 95 which these parts are subjected, therefore, the liability of straining the welded joints is materially reduced.

In addition to the joints above described, there is a joint at the point where the main 100 fire box structure 11 is united with the extended combustion chamber 12. The main weld is on the line *w* and is located between the first row of stay bolts 17 and the second row of stay bolts 18 at the point where the 105 stay bolts of the fire box proper unite with the shaped plates 12^a forming the rear end of the combustion chamber 12. There is

also a right angled weld, as indicated at z , where the round portion of the combustion chamber unites with the shaped portion 12^a of the combustion chamber. This joint is 5 also between the first and second set of rivets 19 and 20.

It will be seen that in every case the line of the weld is supported on one side by a 10 row of stay bolts and on the other side by a row of stay bolts which take a certain proportion of the strain heretofore borne entirely by the weld.

I have not shown the long stays for the 15 back and, in fact, I have omitted from the drawings all unnecessary details which do not relate to the present invention.

While I have illustrated the invention as applied to a boiler of the locomotive type, it will be understood that it can be used in 20 connection with any type of boiler having flanged heads and in which stay bolts are used to connect the fire box and the combustion chamber with the main shell of the boiler.

25 I claim:

1. The combination in a boiler, of a main shell; a back boiler head; a fire box having side walls; a crown sheet; a back head hav-

ing a deep flange secured by welding to the crown sheet and forming the fire box; a 30 series of rows of stay bolts securing the fire box to the main shell of the boiler, one series of stay bolts being secured to the deep flange of the back head so that the welded joint is between the first and second rows of stay 35 bolts.

2. A boiler having in combination inner and outer shells; a back-head and a rear tube sheet, said head and sheet each having a deep flange provided with a row of stay-bolt holes; a welded joint between the flanges of said head and tube sheet and the adjacent portions of the inner sheet; and a plural series of rows of stay bolts, one row of said bolts fitting the holes in the flanges 45 of said head and tube sheet respectively at one side of the weld, and other rows of said bolts fitting corresponding holes in the adjacent portions of the inner shell at the opposite side of the weld thereby localizing 50 each weld between two rows of stay bolts and relieving the weld from excessive strains.

In witness whereof I affix my signature

HENRY V. WILLE.
